(57) **CLAIM**

The ornamental design for an apparatus for measuring light scattering of a sample, as shown and described.

DESCRIPTION

FIG. 1 is a partial front top perspective view of a first embodiment of an apparatus for measuring light scattering of a sample;

FIG. 2 is a partial top perspective view thereof;

FIG. 3 is a front top perspective view of a second embodiment of an apparatus for measuring light scattering of a sample showing my new design;

FIG. 4 is a partial top perspective view thereof;

FIG. 5 is a partial front top perspective view of a third embodiment of an apparatus for measuring light scattering of a sample; and,

FIG. 6 is a partial top perspective view thereof.

The features of the an apparatus for measuring light scattering of a sample shown in broken lines form no part of the claimed design.
